UNITED STATES PATENT OFFICE

WALTER A. TRATSCH, OF CHICAGO, ILLINOIS

CONTROL MECHANISM FOR VENDING MACHINES

Application filed November 9, 1928, Serial No. 318,152. Renewed February 3, 1930.

This invention relates to control mechanisms for vending machines and more particularly to those of the coin operated type, having for its object to provide a mechanism which will be more efficient in operation and less costly to manufacture than those heretofore proposed.

With these and other objects in view the invention consists in the novel details of construction and combinations of parts as will be more fully hereinafter disclosed and particularly pointed out in the claims.

Referring to the accompanying drawings forming a part of this specification in which like numerals designate like parts in all the views,

Fig. 1 is an elevational view of the rear of a mechanism made in accordance with this invention;

Fig. 2 is a top plan view of the parts shown in Fig. 1;

Fig. 3 is a vertical sectional view of the parts illustrated in Fig. 2, taken as on the line 3—3 of said figure and looking in the direction of the arrows;

Fig. 4 is a detail perspective view illustrating the coin trap and coin separating device used in connection with this mechanism;

Fig. 5 is a partial sectional view showing some of the parts illustrated in Fig. 3 in a different position;

Fig. 6 is a detail of some of the parts shown in Fig. 5 in a still different position;

Fig. 7 is a view of the coin slot plate taken as on the line 7—7 of Fig. 3 and looking in the direction of the arrows;

Fig. 8 is a partial perspective view similar to Fig. 4 but showing the parts in slightly different position;

Fig. 9 is a horizontal sectional view taken as on the line 9—9 of Fig. 7 and looking in the direction of the arrows; and

Fig. 10 is a detail view similar to Fig. 5 but illustrating the parts when an unauthorized coin is used in the mechanism.

This mechanism is applicable to many different kinds of vending machines which form no part of this invention. In other words, this invention is directed to a mechanism adapted to be controlled by the insertion of a

coin or trade check which, if of predetermined characteristics, will permit the mechanism to operate the vending machine. On the other hand, the mechanism will not function to operate the vending machine if a coin or other similar device is inserted which does not have the predetermined characteristics. Therefore it will be seen that this mechanism is selective to the end that it will or will not function according to the coin used therein, and it will further be shown to be selective with regard to coins having said predetermined characteristics but possessing slight differences otherwise.

The mechanism consists essentially of a vertical plate 1 which has formed in one face thereof a plurality of recesses or grooves constituting passage-ways for a coin or trade check. That is to say, there are provided grooves 2, 3 and 4 which are substantially parallel, the groove 2 extending from top to bottom of the plate and adjacent one edge thereof. Along one side of this groove there is mounted a magnet 5 for the purpose of diverting an iron or steel disk or washer from the axial line of the groove 2 into a secondary groove 6 freely open at the bottom of the plate as indicated at 9.

In Fig. 7 there is shown in dashed lines the path of travel of an iron washer which has just passed out of the slot 6 to assume the position indicated at 7, said washer being permitted to drop through a chute not shown which expels it from the machine. If, on the other hand, a disk or coin of non-magnetic characteristic is inserted in the groove 2, it will pass the magnet 5 without being deviated from its vertical path, and will therefore fall until it strikes a deflector 8 axially disposed in said grooves and having its upper face so inclined as to cause the coin 10 to roll laterally through an obliquely disposed cross-passage 11 as clearly indicated in Fig. 7 and enter the intermediate groove 3. Here the coin will come to rest on a slide adapted to lift said coin vertically in said groove 3 and cause the coin to roll into and through a transverse passage-way 12 into the top of the third groove 4. Upon entering this groove 4 the coin will 100

drop downwardly therein but come to rest on a trap device presently to be described.

Should there be a coin in the intermediate groove 3 as indicated at 13 when the next subsequent coin is inserted in the mechanism, the subsequent coin if not attracted by the magnet 5 will pass downwardly through the grooves 2 and 11 but when it strikes the previously inserted coin at 13 it will be directed or bounced therefrom so that it will pass reversely through a portion of the groove 11 and roll down through a discharge groove 14 obliquely inclined to cause said subsequently inserted coin to leave the mechanism through the opening 9 as shown at 7 in Fig. 7. 10 15 In a somewhat similar manner, if a coin has reached a position in the groove 4 as indicated at 15 and then a subsequently inserted coin is inserted in the mechanism but which is lacking in a characteristic required to operate the latter, then said subsequently inserted coin will be eventually directed into the groove 4 but when it strikes the coin 15 therein it will be bounced or directed therefrom laterally through the opening 16 and be expelled as indicated at 17 from the mechanism to be returned to the operator of the machine. It is understood of course that this front plate 1 in which the coin grooves are formed is covered by a plate 20 or its equivalent so that the aforementioned grooves will become coin chutes.

This cover plate 20 has mounted thereon the mechanism for controlling the vending machine. That is to say, and with particular reference to Figs. 1, 2 and 3 there is rigidly secured to said plate spaced parallel walls 21 and 22 serving as a mounting for a main operating shaft 23. This shaft is adapted to extend away from said walls, as indicated at 40 45 50 55 60 65 70 75 80 85 90 95 100 105 110 115 120 125 130 outwardly through the casing of the machine and to have secured at its end a suitable handle by means of which the operator of the machine may turn said shaft. Rigidly secured to the shaft 23 is an arm 25 having mounted on one face thereof a couple of headed pins such as 26 adapted to serve as guides for a lifting bar 27 having an elongated slot for each pin as clearly shown in Fig. 3 to 15 20 25 30 35 40 45 50 55 60 65 70 75 80 85 90 95 100 105 110 115 120 125 130 permit limited movement of said bar. The bar 27 has secured to its rear end one end of a spring 28, the other end of which is secured to a pin 29 carried by the arm 25 said spring serving to force the bar 27 in a direction toward the coin lifting slide as shown. The forward end of this bar is angularly bent as indicated at 30 and provided with a finger 31 adapted to project into the coin chute 3 and move in the vertical axial plane thereof.

The coin lifting slide 32 is provided with an aperture 33 through which said finger passes, and in the movement of said finger said slide will be operated. Said plate 32 carries a lug 34 having an obliquely formed upper surface, said lug adapted to fit in the

coin chute 3 and raise a coin from the position shown at 13 in Fig. 7 to the top of the chute, said oblique upper surface causing said coin to be positively directed into and through the cross passage 12 into the coin chute 4. The lug 34, aperture 33 and finger 31 are all so dimensioned and located with respect to the cross passage 11 and the chute 3 that a coin resting on said lug will not only cover said aperture but will cause a subsequently inserted coin to be directed into the discharge chute 14.

Loosely mounted on the shaft 23 is a rocking lever 35 whose rear end is connected as by a heavy duty spring 36 to a pin 37 mounted on the supporting wall 22 which also carries a lug 38 engaging the forward end of said lever to limit the movement thereof under action of said spring. The length of the forward end of said lever is such that when the bar 27 is moved upwardly in the direction of the arrows in Fig. 3 upon rotation of the shaft 23, the extension 30 at the forward end of said bar will clear the extreme end of said lever if the bar has not been pushed back against the tension of its spring 28 by a coin in the chute 3 having a solid center. In other words, the bar 27 in its upward movement will clear the end of the lever 35 as indicated in Fig. 10 when it is operated with either no coin or a centrally apertured trade check in the coin chute 3. The reason for this is that the tension of the spring 28 will cause the bar to remain in the position shown in Fig. 3 or in other words outwardly extended to the full limit permitted by the holding pins 26.

On the other hand if there is a coin or trade check having a solid center in the chute 3 then the end of the finger 31 of the bar 27 in its upward movement will contact with said coin or trade check with the result that said bar will be forced inwardly or to the right as clearly indicated in Figs. 3 and 5. When this occurs the end piece 30 of said bar will strike the under side of the forward end of the lever 35, causing said lever to rock about the shaft 23 against the tension of the spring 36 and in this movement a rod 40 pivotally secured to the rear end of said lever will be actuated to throw a suitable device which will start the actual operation of the vending machine. That is to say the vending is started at the end of the downward movement of said rod and whatever release device is used may be automatically reset by the reverse movement of said rod. No mechanism of this sort is illustrated since it forms no part of this invention.

The rear end of the lever 35 carries a pin 41 to which may be secured the spring 36 said pin normally contacting and supporting one end 42 of a full stroke compelling lever freely pivoted as at 43 to the supporting wall 21, a spring 44 being interposed between the

end 42 of said lever and the arm 25 carried by the shaft 23. Between the pivot 43 and the end 42, the full stroke compelling lever has a lateral extension 45 which when the end 42 is supported as above stated just clears the teeth formed on the arcuate end of a full stroke compelling arm 46 rigidly mounted on the shaft 23 or which may be an integral extension of the arm 25.

10 With particular reference to Figs. 3 and 5 it will thus be seen that when the bar 27 moves upwardly and passes by the end of the rocking lever 35, the teeth of the full stroke compelling arm 46 will pass the extension 45 of the full stroke compelling lever without engaging the same. On the other hand when the bar 27 is forced inwardly, by a requisite coin, it will in its upward movement cause a lifting of the end of the rocking lever 35 next to the coin chute, which will in turn cause a downward movement of the pin 41 at the other end of said lever. This permits the full stroke compelling lever to swing about its pivot 43 bringing the extension 45 thereof into engagement with the teeth of the full stroke compelling arm 46. The full stroke compelling lever is limited in its oscillating movement by a slot 47 disposed in the free end of said lever said slot engaged by 20 a pin 48 carried by the supporting wall 21. Since full stroke compelling devices are well known in the art it is not deemed necessary to make any further statement here regarding the same.

30 35 Also pivoted to the supporting wall 22 as at 50 is a dog 51 having its rear end connected by a spring 52 to the pin 37. The forward end of the dog is rounded and adapted to engage behind the extension 30 of the bar 27 when said bar is moved upwardly. The dog 51 is given its turning movement by a pin 53 extending laterally therefrom and adapted to ride on the upper surface 54 of the arm 25 secured to the shaft 23, see Fig. 6. That is to say, when the bar 27 causes the lever 35 to rock, the extending portion 30 of the former may stick or bind when the bar reaches the limit of its upward movement due to the fact that the resistance of the parts may become considerable through friction and wear. It is essential that the parts be moved to their original positions after each operation of the mechanism in order to insure proper functioning for a subsequently inserted coin. 40 45 Therefore the dog 51 is employed to forcibly move the extension 30 of the bar from its position underneath the forward end of the rocking lever 95 at the end of the movement of the full stroke compelling arm. In other words, the full stroke compelling arm is so disposed on the shaft 23, and the arcuate length of the toothed end of said arm is such that at the end of the engagement between said arm and the full stroke compelling lever, the upper surface 54 of the arm 25 will have

caused, through the pin 53, a movement of the dog 51 which is sufficient to cause the latter to force the extension 30 of the bar 27 out from under the end of the rocking lever 35. When this occurs said lever under the action of its spring 36 will snap back to its normal inoperative position, resting upon the lug 38 provided therefor as can readily be understood from Fig. 6. The dog 51 will be returned to its normal position after the shaft 23 has been reversely rotated by the action of the spring 52.

70 The coin trap is best illustrated in Figs. 4, 7, and 8. The plate 20 covering the coin chute 4 is laterally slotted as at 60 to receive the turned over end 61 of the trap lever 62 pivoted to said plate as at 63, a spring 64 tending to force the turned over end 61 to the limit of said slot. The other end of the lever has an extension 65 adapted to travel across the lower end of the chute 4 to intercept and hold in said chute a coin as indicated at 15 in Fig. 7. When the lever is oscillated, however, the coin will be unsupported and will drop from the bottom of said chute. To keep the extension in position to support a coin there is provided a holding lever 66 pivoted at its upper end to said plate as at 67. This holding lever is substantially L-shaped and bears at its bend against one edge of the upper end of the trap lever. The free end of the holding lever passes through an opening in the wall 22 and is provided with a cam surface 68 adapted to be contacted by a knob 69 formed on one side of the rocking lever 35 100 at the forward end thereof, see Figs. 4, and 8.

90 When the rocking lever 35 is in its normal inoperative position its knob 69 will force and hold the holding lever against the trap lever to cause the extension 65 thereof to intercept and hold a coin in the chute 4. However, when the rocking lever is oscillated the knob thereof will move out of contact with the holding lever, at which time the spring 64 will cause the trap lever to oscillate within the limits of the slot 60 in its supporting plate 20 and thus swing the extension 65 from beneath the coin shown at 15. The oscillation of said lever 35 is only caused by a requisite coin or trade check and therefore the trap lever is provided with the turned over end 61 which, during said oscillation is moved into the chute 4 to intercept the coin controlling said oscillation, and the cross passage 12 is inclined downwardly toward said chute 4 to prevent said coin leaving the latter. When the rocking lever again assumes its normal inoperative position its knob will contact the cam surface of the holding lever, causing the latter to move the upper end 61 of the trap lever to release the subsequently inserted coin and simultaneously move the lower end 65 of said lever into position to intercept the coin just released by its other end. A coin while held by the lower end of the 110 115 120 125 130

trap lever will be in full view of the operator of the machine by the provision of a sight hole or window 76 in the front wall of the device.

The coins or trade checks released by the trap lever will fall into an open ended inclined trough 70 provided in its bottom with an opening 71, and beneath said opening is a second inclined trough 72 leading to the top of a coin box 73. All coins released by the trap lever will fall into the trough 70 but the opening 71 therein is spaced closer to one side thereof and said trough is tilted so that coins of lesser diameter, as indicated at 74 in Fig. 4, will fall through said opening into the second trough 72 while larger coins as indicated at 75 in said figure will bridge said opening and fall out the open end of the trough 70 into a separate coin box.

There are four types of disk which are used in attempts to operate vending machines. One is the coin which is intended for use; another is a solid non-magnetic disk known as a trade check which may be authoritatively used in place of money in the establishment where the vending machine is located; the third type is an iron or steel disk or washer which is used fraudulently; and the fourth type is a non-magnetic disk likewise known as a trade check but which has a hole in its center and which is not intended for use in said establishment. As stated hereinbefore, the iron or steel washers will be drawn by the magnet 5 out of the coin chute 2, but the other types of disks being non-magnetic will pass into the chute 3, and be raised by the slide 32. However, those disks having a central aperture will not permit operation of the vending machine because the finger 31 of the bar 27 will pass through said aperture and thus prevent said bar from being moved into position to rock the lever 35. These apertured disks will therefore pass through the coin chutes 2 and 3 and be eliminated through the opening 16 from the chute 4 as indicated see Fig. 7. It will thus be seen that the only disks which will operate the machine are actual coins or solid non-magnetic disks, and therefore by "predetermined characteristics" is meant such disks.

This control mechanism is designed for a machine intended to vend merchandise or to give some sort of amusement to the value of ten cents, and to this end the coin chute 2 is dimensioned for a dime, thus automatically making impossible the use of any other coin. Trade checks are made of a diameter different from that of coins and therefore the trough 70 is provided with the aperture 71 for the purpose of separating the coins from the trade checks.

From the foregoing it will thus be seen that this mechanism comprises a coin chute having passages in different planes and so communicating that a coin may be passed from the inlet to and through the chute to the discharge

chute and that while the coin is so traversing the chute it may cause a reciprocable bar to be moved into locking position with means to actuate the vending mechanism, all in accordance with the predetermined characteristic of the coin. The chute is provided with a slide which is actuated by means comprising a rotatable shaft, an arm attached thereto, a bar reciprocably mounted under spring tension on said arm said bar having a finger engaging the slide and adapted to enter the chute, and when the coin having a solid center (predetermined characteristics) is in position on the slide it will obstruct the chute to the extent of not permitting the end of the finger to enter said chute. When this situation exists the finger being rigid with the bar will cause the latter to be moved against the spring tension thereof whereupon a lateral extension of said bar will come into locking contact with the rocking lever so that continued moving of the said bar in an arcuate direction about the shaft will cause the rocking lever to move and actuate the vending mechanism.

When the central apertured disk is on the slide, however, the end of the finger will be unobstructed, or in other words may pass through the hole in said disk, entering the coin chute and therefore permitting no reciprocation or sliding movement of the bar into locking position with the rocking lever. It may therefore properly be stated that the means to move the slide in the coin chute is governable by a coin of predetermined character in order to move the rocking lever which actuates the vending mechanism.

It is obvious that those skilled in the art may vary the details of construction as well as arrangements of parts without departing from the spirit of the invention and it is therefore not desired to be limited to the foregoing except as may be required by the claims.

What is claimed is:—

1. In a device of the character described a coin chute comprising a plurality of passages in different vertical planes communicating with a common inlet; means associated with one of said passages for moving a coin therethrough; means associated with another passage for releasing a previously inserted coin; and operating mechanism for actuating said first and second named means.

2. In a device of the character described a plurality of parallelly disposed coin chutes joined by cross-passages; a slide in one of said chutes for moving a coin therethrough; a shaft and means therewith to move said slide; means associated with the discharge chute for retaining a previously inserted coin; and means for releasing the retaining means.

3. In a device of the character described a plurality of parallelly disposed coin chutes joined by cross-passages; a slide in one of said chutes for moving a coin therethrough; a

shaft and means therewith to move said slide; means associated with the discharge chute for retaining a previously inserted coin; and means for releasing the retaining means said means controlled by the first mentioned means.

4. In a device of the character described a plurality of parallelly disposed coin chutes joined by cross-passages; a slide in one of said chutes for moving a coin therethrough; a shaft and means therewith to move said slide said means cooperating with the coin moved by said slide; means associated with the discharge chute for retaining a previously inserted coin; and means for releasing the retaining means.

5. In a control for vending mechanism in combination a coin chute adapted to receive disks with solid or open centers said chute comprising a vertical passageway for receiving the inserted disk and permitting its travel therethrough, a second vertical passageway communicating with said first mentioned passageway to receive disks from said first mentioned passageway, and a third vertical passageway communicating with said second passageway to receive and discharge the disks therefrom; a slide in said second passageway for causing a disk therein to move to and into said third passageway; and means to operate said slide said means connected to the vending mechanism to actuate the same when said slide is moving a disk with a solid center.

35 6. In a control for vending mechanism in combination a coin chute adapted to receive disks with solid or open centers said chute comprising a vertical passageway for receiving the inserted disk and permitting its travel therethrough, a second vertical passageway communicating with said first mentioned passageway to receive disks from said first mentioned passageway, and a third vertical passageway communicating with said second passageway to receive and discharge the disks therefrom; a slide in said second passageway for causing a disk therein to move to and into said third passageway; and means to operate said slide said means cooperating with the disks moved thereby and connected to the vending mechanism to actuate the same when said slide is moving a disk with a solid center and disconnected from said mechanism when said slide is moving a disk with an open center.

7. In a control device for a vending mechanism the combination of a coin chute; a slide in said chute to move a coin therein; means to actuate the vending mechanism; an operating shaft; and means carried by said shaft to move said slide, said means being governable by a coin of predetermined character to move said first named means.

8. In a control device for a vending mechanism the combination of a coin chute; a slide

in said chute to move a coin therein; means to actuate the vending mechanism; an operating shaft; and means carried by said shaft adapted to enter said chute to move said slide, said means being governable by a coin of predetermined character to move said first named means.

9. In a control device for a vending mechanism the combination of a coin chute; a slide in said chute to move a coin therein; means to actuate the vending mechanism; an operating shaft; and means to move said slide said means comprising an arm rotatable with said shaft, a bar reciprocably mounted on said arm and provided with a finger engaging said slide and adapted to enter said chute, said bar being moved into engagement with said first named means when a coin of predetermined character stops said finger from entering said chute.

10. In a control device for a vending mechanism the combination of a coin chute; a slide in said chute to move a coin therein; means to actuate the vending mechanism; an operating shaft; and means to move said slide said means comprising an arm rotatable with said shaft, a bar reciprocably mounted on said arm and provided with a lateral extension as well as with a finger engaging said slide and adapted to enter said chute, the extension of said bar being moved into engagement with said first named means when a coin of predetermined character stops said finger from entering said chute.

In testimony whereof I affix my signature. 100
